PUSH BACK CHAIR

Joseph Eckert and Elof P. Klar, Menominee, Mich., assignors to Heywood-Wakefield Company, Gardner, Mass., a corporation of Massachusetts

Application December 14, 1949, Serial No. 132,952

8 Claims. (Cl. 155—116)

1

This invention relates to improvements in push back chairs and it consists of the matters hereinafter described and more particularly pointed out in the appended claims.

One of the objects of the present invention is to provide a push back chair of simple construction, in which the seat thereof may be readily moved rearwardly by the occupant to permit the passing of persons in the space between rows of seats, and again be as readily moved forwardly by the occupant without rising from the seat.

Another object of the invention is to provide, in a chair of this kind, a novel arrangement in the supporting linkage for the seat, whereby the seat may be readily moved in either direction between its forward and rearward positions and at the same time cause the back to move into that position most comfortable for the occupant, when the seat is in either of its positions.

Also, it is an object of the invention to provide a chair of this kind wherein the parts for supporting the seat and back from the side standards are reduced to a minimum and are so relatively arranged with respect to each other and to the seat and the back as to eliminate the pinching and tearing hazards to the fingers and clothing.

The above mentioned objects of the invention, as well as others, together with the advantages thereof, will more fully appear as the specification proceeds.

In the drawings:

Fig. 1 is a perspective view of a theatre type chair embodying the preferred form of the invention, with the seat thereof in its forward position.

Fig. 2 is a vertical sectional view through the chair, as taken on the line 2—2 and on a scale enlarged over that of Fig. 1, with the seat in its rearward position and with the seat cushion shown only in dotted lines.

Fig. 3 is a detail vertical sectional view, as taken on the line 3—3 and on a scale enlarged over that shown in Fig. 2.

Fig. 4 is a view similar to Fig. 2 and shows the arrangement of the parts of the chair, when the seat is in the forward position appearing in Fig. 1.

Figs. 5 and 6 respectively are detail horizontal sectional views, as taken on the lines 5—5 and 6—6 respectively of Fig. 2 and on a scale enlarged thereover.

Referring now in detail to that embodiment of the invention illustrated in the drawings, the improved chair includes, among the parts thereof, a pair of laterally spaced upright supports or standards 10—10. In this instance each standard comprises a sheet metal body 11, having inwardly turned front and rear margins 12 and 13 respectively. Fixed to the inner face of and ex-

2

tending from top to bottom of each margin is a stiffener bar 14 (see Fig. 5). Each bar has a T shaped cross section with the flanges thereof fixed to said margins and with the webs 15 of said bars disposed in the same plane and facing one another. The webs 15 of both bars of each standard are connected together by a vertically edgewise disposed relatively wide metal strap 16, a suitable distance above the bottom of the standard, which is formed to engage upon and be secured in any suitable manner to a supporting surface, such as a floor. At the top of each standard is an arm rest 17. The plate 16 not only stiffens and braces the associated standard, but forms a part fixed relatively thereto and from which the seat and back, later mentioned, are supported.

Spaced inwardly from the upper margin of each strap 16 and extending above and below the top edge thereof is a vertically disposed plate 18 mounted for forward and rearward movement. The plates 18 at the sides of the chair are connected together by a tubular reach bar 19. That part 20 of each plate, rearwardly of the associated end of the reach bar, is offset inwardly from the remainder of the plate, as best shown in Fig. 5.

On the inner face of each plate, toward its front edge, is secured a bracket 21 that includes a downwardly tapering socket 22. These sockets detachably receive stems 23 depending from opposite sides of a seat bottom 24 in the form of a shallow pan. This pan receives and supports the spring and upholstery assembly 25 of the seat. As this assembly may be of any suitable kind and forms no particular part of the invention, it is not thought necessary to illustrate or describe the same in detail.

The back of the chair, which is indicated as a whole at 26, includes a sheet metal back plate 27 with suitable upholstery 28 on the front thereof. At each side of the back plate, toward the bottom thereof, there is a forwardly extending wing 29, the front end of which is formed as a downwardly and forwardly inclined extension 30. The bottom portion of each wing is pivotally attached as at 31 to the inwardly offset portion 20 of the plate 18 at the same side of the chair. The front of the inclined extension 30 is provided with an outturned flange 32, which is extended to the upper end of the wing and materially stiffens the same.

At each side of the sheet is a generally upright supporting link 33, the bottom end of which is pivotally connected at 34 to the bottom margin of the associated strip 16 toward its front end. The upper end of each link 33 is disposed in the plane of the flange 32 of the associated wing 29 and it is pivotally connected thereto as at 35 at the upper end of the extension 30. The links

33 at both sides of the seat are connected together by a tubular member 36 disposed just below the seat pan 24.

Also at each side of the seat is a second and generally upright link 37, disposed in a plane outwardly from the link 33 at the same side of the seat. Each link 37 has a length greater than that of the associated link 33 and each set of links 33-37 is pivotally connected together at a point between the ends thereof, as indicated at 38. The bottom end of each link 37 is pivotally connected as at 39 to the front lower corner of an associated plate 18, and the top end of each link 37 is pivotally connected as at 40 to the front end of an associated radius link 41. The rear end 15 of each radius link, which is disposed in a generally horizontal position, is pivotally connected as at 42 to a plate 43 disposed in the upper rear end corner of the associated standard 10.

About midway of each plate 18 there depends from the bottom edge thereof a stud 44 enclosed in a cushioning sleeve 45 of rubber or the like and which functions, as the seat is moved rearwardly of the chair, to engage against a stop 46 which projects inwardly from the associated strip 16.

On the upper end of the inside of each standard, disposed between each wing 29 and the upper end of the associated link 37, there is fixed thereto a guard plate 47, which extends to a 30 position below the top of the seat. This plate conceals the linkage parts in the upper end of each standard and eliminates the pinching and tearing hazards to the fingers and clothing of the occupant.

The seat 25 is shown in its rearward position in Fig. 2 and in this position the front thereof extends a short distance forwardly of the front of the standards 10-10 and the back 26 is disposed slightly to the rear of the standards and has a 40 contour (vertically considered) that matches the rear edges of the standards.

At this time the cushions 45 are engaged against the stops 46 and the front edge of the upper end of both links 33 are engaged with the 45 under side of that part of the flange 32 of the associated wing 29 at the front of the extension 30 thereof. In this position the seat supporting plates 18 are supported by those parts of the links 33-37 below the pivotal connection 38 and by reason of the engagement of the upper end of the links 33 with the underside of the flanges 32 on the wing extensions 30 and by reason of the engagement of the cushions 45 with their stops.

When the occupant assumes a position on the seat, and the parts are in the position above described, the feet of the occupant are engaged upon the supporting surface or floor upon which the chair is supported. By flexing the knees and moving the body forwardly, the seat is shifted 60 forwardly of the standards to the position shown in Fig. 4. In this movement of the body, the links 33 swing toward a perpendicular position and as the links 37 are pivoted thereto as at 38, the links 37 swing about their pivotal connection 65 with the radius links 41. In this movement of the linkage as the pivotal connections 39 swing forwardly through the vertical plane of the pivotal connection 40, the links 37 will rise slightly and in this movement their upper ends are 70 guided by the radius links. When the links 33 have swung to the position shown in Fig. 4, they will, through the pivotal connection 38, cause the lower ends of the links 37 to swing forwardly and to a position wherein the plane of each 75

4
pivotal connection 39 is above and slightly forwardly of the pivotal connection 34 and this forms an overcenter lock for the linkage which holds the seat in the forward position, under the weight of the occupant and wherein it slopes downwardly toward the rear.

In the forward movement of the seat, the back plate 27, by reason of the pivotal connections 31 and 35, will move forwardly and into a more inclined position, which will be more comfortable for the occupant.

When the occupant rises from the seat, the backs of the legs are so disposed with respect to the front, that a slight rearward push on the front of the seat will move the axis of the pivotal connection 39 from a point forwardly of the axis of the pivotal connections 34 to a point rearwardly thereof, whereby the weight of the unoccupied seat and back will cause them to return to the position shown in Fig. 2.

The parts of the chair are relatively few in number and simple in construction, and function in a quiet and easy manner and this through almost the unconscious action of the person to occupy or leave the chair.

In the illustrations but a single chair is shown, in which event two separate and independent standards are necessary. While in describing the invention we have referred in detail to the form, construction and arrangement of the parts embodied therein, the same is to be considered only in the illustrative sense and therefore we do not wish to be limited thereto except as may be specifically set forth in the appended claims.

We claim as our invention:

1. A push back chair embodying therein laterally spaced standards, a forwardly and rearwardly movable member inwardly of each standard, a seat supported at least in part by said movable members, a back, a forwardly extending arm portion at each side of the back, means pivotally connecting each forwardly extending arm portion to an associated movable member, a link at each side of the seat and pivotally connected at its lower end to one of said movable members, means providing a guided movement for the upper end of each said link, a second link at each side of the seat and pivotally connected at its bottom end to a fixed part on a standard on the same side of the seat and pivotally connected at its top end to one of said arm portions, and means pivotally connecting the first and second mentioned links at each side of the seat together at points between their ends.

2. A push back chair embodying therein laterally spaced standards, a forwardly and rearwardly movable member inwardly of each standard, a seat supported at least in part by said movable members, a back, a forwardly extending arm portion at each side of the back, means pivotally connecting each forwardly extending arm portion to an associated movable member, a link at each side of the seat and pivotally connected at its lower end to one of said movable members, a substantially horizontally disposed radius link pivotally connected to the upper end of each link and to a fixed part of the associated standard respectively and providing a guided movement for the upper end of each link, a second link at each side of the seat and pivotally connected at its bottom end to a fixed part of the standard on the same side of the seat and pivotally connected at its top end to one of said arm portions, and means pivotally connecting the first and second mentioned links at each side of the seat together at points between their ends.

necting the first and second links at each side of the seat together at points between their ends.

3. A push back chair embodying therein laterally spaced standards, a forwardly and rearwardly movable member inwardly of each standard, a seat supported at least in part by said movable members, a back, a forwardly extending arm portion at each side of the back, means pivotally connecting each forwardly extending arm portion to an associated movable member, a link at each side of the seat and pivotally connected at its lower end to one of said movable members, means providing a guided movement for the upper end of each said link, a second link at each side of the seat and pivotally connected at its bottom end to a fixed part on a standard on the same side of the seat and pivotally connected at its top end to one of said arm portions, means pivotally connecting the first and second mentioned links at each side of the seat together at points between their ends, and means carried by at least one of said arm portions and adapted for engagement with a part of the associated second link spaced from its pivotal connection with said arm portion and forming at least a part of a stop for limiting the rearward movement of the seat.

4. A push back chair embodying therein laterally spaced standards, a forwardly and rearwardly movable member inwardly of each standard, a seat supported at least in part by said movable members, a back, a forwardly extending arm portion at each side of the back, means pivotally connecting each forwardly extending arm portion to an associated movable member, a link at each side of the seat and pivotally connected at its lower end to an associated movable member, means providing a guided movement for the upper end of each said link, a second link at each side of the seat and pivotally connected at its bottom end to a fixed part on a standard on the same side of the seat and pivotally connected at its top end to one of said arm portions, means pivotally connecting the first and second mentioned links at each side of the seat together at points between their ends, and means carried by said movable member and arranged for engagement with a part fixed with respect to the adjacent standard and forming at least a part of a stop for limiting the rearward movement of the same movable member.

5. A push back chair embodying therein laterally spaced forwardly and rearwardly movable members, a seat supported at its sides from said movable members, a back, a forwardly extending arm portion at each side of the back and each pivoted to a movable member, a link at each side of the seat and pivotally connected at its lower end to an associated movable member, means providing a guided movement for the upper end of each said link, a second link at each side of the seat and pivotally connected at its bottom end to a fixed point for a swinging movement and pivotally connected at its top end to an associated arm portion, and means pivotally connecting the first and second links at each side of the seat together at a point between their ends.

6. A push back chair embodying therein laterally spaced forwardly and rearwardly movable members, a seat supported at its sides from said

movable members, a back, a forwardly extending arm portion at each side of the back and each pivoted to a movable member, a link at each side of the seat and pivotally connected at its lower end to an associated movable member, means providing a guided movement for the upper end of each said link, a second link at each side of the seat and pivotally connected at its bottom end to a fixed point for a swinging movement and pivotally connected at its top end to an associated arm portion, and means pivotally connecting the first and second links at each side of the seat together at a point between their ends, each of said arm portions including a flange for engagement with a part of the associated second link for limiting the rearward movement of the seat.

7. A push back chair embodying therein laterally spaced standards including inturned front and rear flanges, a plate connecting the flanges of each standard and arranged inwardly of the body of the latter, a forwardly and rearwardly movable member, inwardly of each plate, a seat supported by said movable members, a back, a forwardly extending arm portion at each side of the back, means pivotally connecting each arm portion to an associated movable member, a link at each side of the seat and pivotally connected at its lower end to an associated movable member, means providing a guided movement for the upper end of each said link, a second link at each side of the seat and pivotally connected at its bottom end to an associated plate and pivotally connected at its top end to an associated arm portion, and means pivotally connecting the first and second mentioned links at each side of the seat together at points between their ends.

8. A push back chair embodying therein laterally spaced standards including inturned front and rear flanges, a plate connecting the flanges of each standard and arranged inwardly of the body of the latter, a forwardly and rearwardly movable member, inwardly of each plate, a seat supported by said movable members, a back, a forwardly extending arm portion at each side of the back, means pivotally connecting each arm portion to an associated movable member, a link at each side of the seat and pivotally connected at its lower end to an associated movable member, means providing a guided movement for the upper end of each said link, a second link at each side of the seat and pivotally connected at its bottom end to an associated plate and pivotally connected at its top end to an associated arm, means pivotally connecting the first and second mentioned links at each side of the seat together at points between their ends, and coacting means on each movable member for engagement with a fixed part on the associated plate to limit the rearward movement of the seat.
